ACID RESISTANT AUSTENITIC STAINLESS STEEL

Raymond Smith, Pittsburgh, Pa., and Charles O. Tarr, Glendale, Ohio, assignors to United States Steel Corporation, a corporation of New Jersey

No Drawing. Continuation of application Serial No. 450,785, August 18, 1954. This application November 6, 1957, Serial No. 694,728

4 Claims. (Cl. 75—125)

This application relates to acid resistant stainless steels and more particularly to forgeable stainless steels that have enhanced resistance to mineral acids such as sulphuric acid.

Stainless steels have heretofore been known which are resistant to corrosive attack by mineral acids. However, such steels have generally been used in cast form since they can only be processed to wrought form by taking severe losses in forging operations or by very special and expensive processing operations which seriously affected the size and shapes that could be so processed.

It is accordingly an object of this invention to provide austenitic stainless steels resistant to mineral acid corrosion which are readily forgeable.

It is a further object of this invention to produce forgeable stainless steels which have a satisfactory resistance to boiling 30% sulphuric acid.

It is another object of this invention to provide acid corrosion resistant stainless steels which are comparatively economical to produce.

According to the teachings of our invention, the foregoing objects can be achieved in steels of the following composition:

	Percent
Carbon	0.1 to .10
Manganese	.15 to 2.0
Silicon	.75 max.
Sulphur	.04 max.
Phosphorus	.04 max.
Nickel	23.0 to 27.0
Chromium	17.0 to 20.0
Molybdenum	.80 to 1.5
Copper	.80 to 1.5
Titanium	.20 to 2.0

We have discovered that the relatively large amounts of silicon, i. e. over 1%, frequently used to obtain enhanced corrosion resistance are very detrimental to forging qualities, whereas with less than about .75% silicon, satisfactory forgeability is obtained. While less than .75% silicon is desirable, it is hard to obtain with present steelmaking techniques. The influence of silicon on forgeability is evident from the following Table I:

Table I

Heat No.	C	Mn	Si	Ni	Cr	Mo	Cu	Hot Forgeability
1	.06	1.1	.45	17.56	16.86	.98	.99	Satisfactory.
2	.06	1.0	.85	18.00	17.00	1.00	1.00	Fair.
3	.06	1.0	1.65	18.00	17.00	1.00	1.00	Unsatisfactory.
4	.05	1.1	2.02	18.52	15.90	.95	1.08	Do.
5	.20	1.0	2.00	18.00	17.00	1.00	1.00	Do.
6	.06	1.0	1.77	18.00	17.00	3.00	1.00	Do.
7	.06	1.1	2.12	18.52	16.40	1.04	2.82	Do.
8	.06	1.2	2.00	22.00	17.00	1.00	1.00	Do.
9	.06	.80	.64	22.75	16.37	1.02	1.00	Satisfactory.
10	.07	1.4	.57	21.98	16.74	1.02	1.00	Do.

However, lowering the silicon content to develop satis-

2

factory forgeability lowers the corrosion resistance. We have discovered that the corrosion resistance can be restored and even improved by the addition of titanium in amounts over .20% and up to about 2%, particularly if the nickel content is increased slightly. If titanium is added in amounts over 2%, objectionable "stringers" are encountered. The effect of lowering silicon and addition of titanium on corrosion resistance to boiling 30% by weight sulphuric acid is shown in the following Table II. As can be seen reducing silicon increases the corrosion rate to more than .006 I. P. M. (inches penetration per mouth) which is regarded as unsatisfactory.

Table II

Heat No.	C	Mn	Si	Ni	Cr	Mo	Cu	Ti	Corro- sion, I. P. M. Boiling 30% H ₂ SO ₄
11	.05	1.1	2.02	18.52	15.90	.95	1.08	—	.005
12	.06	1.0	1.65	18.00	17.00	1.00	1.00	—	.014
13	.06	1.0	.85	18.00	17.00	1.00	1.00	—	.022
14	.06	1.1	.45	17.50	16.86	.98	.99	—	.015
15	.07	1.35	.46	23.72	16.77	1.02	.98	—	.008
16	.06	1.30	.55	24.16	16.70	1.00	1.00	.41	.004
17	.051	—	—	24.00	17.00	1.00	1.00	.15	.007
18	.049	—	—	24.00	17.00	1.00	1.00	—	—
19	.062	1.36	.60	21.96	17.04	.99	1.02	.32	.005

A comparison of the corrosion data for heats 15, 16, 17 and 18 demonstrates clearly the ability of titanium to lower the corrosion rate to less than .006 I. P. M. This may result from the ability of titanium to scavenge nitrogen and sulphur from the material.

The following Table III demonstrates that substantial resistance to boiling 30% sulphuric acid is obtained with about 1% each of molybdenum and copper when titanium is present.

Table III

Heat No.	C	Mn	Si	Ni	Cr	Mo	Cu	Ti	Corro- sion, I. P. M. Boiling 30% H ₂ SO ₄
20	.05	1.1	2.02	18.0	17.0	1.0	1.0	—	.00515
21	.05	1.1	1.85	18.0	17.0	2.0	2.0	—	.00435
22	.05	1.3	.47	22.0	15.0	1.0	3.0	.42	.00407
23	.06	1.5	.54	22.0	17.0	1.0	1.0	.50	.00493

However to adequately resist attack in boiling 50% by weight sulphuric acid, i. e. to reduce the I. P. M. to about .01% or less, higher molybdenum is required. This is shown in Table IV.

Table IV

Heat No.	C	Mn	Si	Ni	Cr	Mo	Cu	Ti	Corro- sion, I. P. M. Boiling 50% H ₂ SO ₄
24	.062	.80	.64	22.75	16.87	1.02	1.00	.42	.063
25	.049	1.40	.40	21.39	16.12	2.85	.98	.04	.0103
26	.050	1.28	.51	22.00	16.88	2.95	1.02	.50	.0083

These higher molybdenum contents contribute to poor hot working characteristics.

Numerous experiments have shown that titanium is unique in respect to enhancing corrosion resistance. The following Table V shows that the elements such as vanadium, columbium, tantalum, tungsten, and zirconium which are sometimes considered equivalents to titanium do not react in the same way as titanium in this respect.

Table V

Heat No.	C	Mn	Si	Ni	Cr	Mo	Cu	Others	Corro- sion, I. P. M. Boiling 30% H ₂ SO ₄
27	.066	1.40	.57	21.98	16.74	1.02	1.00	.37 Ti	.0055
28	.056	1.29	.59	21.82	17.11	1.03	1.00	.57 V	.0104
29	.059	1.28	.53	22.30	17.32	1.07	.98	1.01 Cb	.0084
30	.068	1.34	.54	21.20	16.90	1.03	.97	.76 W	.0107
31	.062	1.50	.63	21.20	16.72	1.03	.97	1.20 Cb+Ta	.0096
32	.059	1.38	.58	22.40	16.80	1.03	1.01	.49 Zr	.0199

In view of extensive tests, as exemplified by the foregoing tables, we have found that considering the economies of manufacture, the following ranges are preferred:

	Percent	
Carbon	.05 to .08	
Manganese	.75 to 1.50	20
Silicon	.60 max.	
Phosphorus	.04 max.	
Sulphur	.04 max.	
Nickel	23.00 to 27.00	
Chromium	17.00 to 20.00	25
Molybdenum	.80 to 1.50	
Copper	.80 to 1.50	
Titanium	.30 to .50	

This application is a continuation of my copending application Serial No. 450,785, filed August 18, 1954, now abandoned.

While we have shown and described several specific embodiments of our invention, it will be understood that these embodiments are merely for the purpose of illustration and description and that various other forms may be devised within the scope of our invention, as defined in the appended claims.

We claim:

1. A readily forgeable austenitic stainless steel highly resistant to corrosion by mineral acids and characterized by an I. P. M. rate of less than .006 in boiling 30% sulphuric acid, said steel consisting of

	Percent	
Carbon	.05 to .08	
Manganese	.75 to 1.50	43
Silicon	.60 max.	
Phosphorus	.04 max.	
Sulphur	.04 max.	
Nickel	23.00 to 27.00	
Chromium	17.00 to 20.00	
Molybdenum	.80 to 1.50	
Copper	.80 to 1.50	
Titanium	.30 to .50	

with the balance iron and residual amounts of other elements.

2. A readily forgeable austenitic stainless steel highly resistant to corrosion by mineral acids and characterized by an I. P. M. rate of less than .006 in boiling 30% sulphuric acid, said steel consisting of

	Percent	
Carbon	.05 to .08	
Manganese	.75 to 1.50	
Silicon	.60 max.	
Phosphorus	.04 max.	65
Sulphur	.04 max.	
Nickel	23.00 to 27.00	
Chromium	17.00 to 20.00	
Molybdenum	.80 to 1.50	
Copper	.80 to 1.50	
Titanium	.30 to .50	70

with the balance iron and other elements in amounts which do not adversely affect the properties.

3. A readily forgeable austenitic stainless steel highly resistant to corrosion by mineral acids and characterized by an I. P. M. rate of less than .006 in boiling 30% sulphuric acid, said steel consisting of

	Percent
Carbon	.01 to .10
Manganese	.15 to 2.00
Silicon	.75 max.
Sulphur	.04 max.
Phosphorus	.04 max.
Nickel	23.00 to 27.00
Chromium	17.00 to 20.00
Molybdenum	.80 to 1.50
Copper	.80 to 1.50
Titanium	.20 to 2.00

with the balance iron and residual amounts of other elements.

4. A readily forgeable austenitic stainless steel highly resistant to corrosion by mineral acids and characterized by an I. P. M. rate of less than .006 in boiling 30% sulphuric acid, said steel consisting of

	Percent
Carbon	.01 to .10
Manganese	.15 to 2.00
Silicon	.75 max.
Sulphur	.04 max.
Phosphorus	.04 max.
Nickel	23.00 to 27.00
Chromium	17.00 to 20.00
Molybdenum	.80 to 1.50
Copper	.80 to 1.50
Titanium	.20 to 2.00

with the balance iron and other elements in amounts which do not adversely affect the properties.
